UNITED STATES PATENT OFFICE.

WILLIAM G. KENDALL, OF NEWARK, NEW JERSEY.

HOLDING RING FOR COMPACT PLATES.

Application filed March 8, 1928. Serial No. 260,082.

This invention relates to holding rings for compact plates, and has for an object to provide an improved construction which may be arranged in different forms of cases 5 and function to resiliently and yieldingly hold a compact plate in the case.

Another object of the invention is to provide an L-shaped holding ring for holding compact plates in position, the construction 10 being such that projections from part of the ring act as yielding locking means for holding the compact plate in position.

A further object is to provide a holding ring which may be an L or Z-shaped structure in cross section, but formed with resilient portions acting to pinch and hold a compact plate in position.

In the accompanying drawing—

Figure 1 is a plan view of a vanity case 20 shown open and provided with a compact plate and holding ring embodying the invention.

Figure 2 is a sectional view through Figure 1, approximately on line 2—2.

Figure 3 is a view similar to Figure 2, but showing a holding ring substantially Z-shaped in cross section.

Figure 4 is a perspective view of a holding ring disclosing a modified structure to that 30 illustrated in Figure 2.

Figure 5 is a perspective view of a holding ring of the type shown in Figure 4, but illustrating a Z-shaped structure in cross section as illustrated in Figure 3.

Figure 6 is a perspective view of a holding ring, disclosing a further modified form of the invention.

Referring to the accompanying drawing by numerals, 1 indicates the body of a vanity 40 case of any desired kind having a suitable lid 2 hingedly connected to the body 1. As is usual in many vanity cases, the bottom 3 of body 1 is rounded at the edges, and to properly hold a compact plate 4 in the body, 45 a holding ring 5 L-shaped in cross section is provided as illustrated particularly in Figure 2. The top or radial flange 6 projects slightly underneath the usual retaining ring 7, while the vertical section or tubular portion 8 projects downwardly and rests on the bottom 3. It will be seen from Figure 2 that the locking ring 7 is fitted into the annular groove 21 formed by the turned-over flange 22 of the casing. The ring 7 projects a 55 short distance beyond the groove 21 in order to overlap part of the flange 6 so as to hold

the ring 5 in place. It is evident that the ring 5 could interlock with other parts where the body was formed in some other manner, the essentials being the provision of a substantially L-shaped structure provided with one or more pressed out portions 9 presenting nibs or projections adapted to press against and somewhat interlock with the plate 4. The ring 5 is made preferably of very thin sheet metal and when the portion 9 is pressed therefrom, a resilient lock is presented beneath which part of the plate 4 snaps when the plate is placed in operative position. In case the plate 4 is provided 60 with a straight vertical side wall, the projections 9 press against the same and frictionally hold the plate in position, though if desired, one or more of the projections 9 could be pressed out at the top of the section 65 8 so as to somewhat overlap the upper edge of the plate. In any form or embodiment 70 of the invention, there is always present the substantially L-shaped structure with pressed out portions interlocking or pressing against 75 some part of the compact plate for holding the plate resiliently and yieldingly in place.

In Figure 3, a slightly modified structure is disclosed, wherein the bottom 10 of the compact plate 4', is appreciably rounded and 80 in order to take care of this properly, the ring 5' is formed substantially Z-shaped in cross section so as to have a horizontal portion 6', a vertical portion 8', and a projecting or supporting portion 11 overlapping 85 the compact plate 4'. In this form of the invention, preferably the pressed out portion 9' is raised to a point near the top of the ring 5' so as to better engage the plate 90 for holding the same resiliently in position.

In Figure 4, a further modified form of the invention is shown, wherein the ring 5'' is constructed substantially identical with that shown in Figure 2, except instead of having pressed out portions 9, slits or slots 100 12 are formed in the vertical section 8''. This presents a number of independent resilient fingers 13 adapted to press against or pinch a compact plate for holding the same 105 in proper position in a vanity case.

In Figure 5, a further modified form of the invention is shown to that illustrated in Figure 4, said modification consisting in having a ring similar to ring 5', but provided with slots or slit 14 whereby not only vertical fingers 13 are presented, but horizontal supporting fingers 15 are provided. This 110

form of ring may be used with any desired form of compact, as for instance, that shown in Figure 2, though preferably it is intended for some kind of a compact similar to that illustrated in Figure 3 where the side edges of the compact should be supported to prevent rocking.

In Figure 6, a further modified form is shown, wherein a holding ring L-shaped 10 in cross section is provided, and the tubular portion 16 is provided with a number of cuts 17 whereby tongues 18 are presented adapted to overlap part of the compact plate. In the drawing, only three tongues 15 have been shown, but it is evident that a greater number or even a less number might be used without departing from the spirit of the invention. However, these tongues are preferably pressed out slightly beyond 20 the section 16 to present resilient projections, and also preferably these tongues are not as numerous as those shown in Figure 4.

In regard to the form of the invention shown in Figures 2 and 3, it will be noted 25 that there is provided a space 19 between the compact plate and the holding ring. This space is designed to be utilized by an implement of any desired kind, as, for instance, a manicure scissors or nail file. 30 When an implement is inserted in the space 19 and pressed against the vertical wall of the compact plate and given a swinging movement in the manner of the lever acting against the edge 20, the implement will 35 eject or remove the compact plate. In the form shown in Figures 4 and 5 the nail file or other implement is adapted to be inserted into one of the cuts 12 and then against the compact plate, after which a 40 swinging upward movement is given to pry

out the compact plate. In this way, a compact plate is readily removed or ejected.

What I claim is:

1. The combination of a compact plate and a holding ring, comprising a holding ring 45 having a tubular portion and a compact plate having a substantially annular upstanding wall spaced from said tubular portion, whereby an implement-receiving space is provided for permitting an implement to 50 press against said annular wall and eject the compact plate.

2. The combination of a holding ring having a tubular portion and a compact plate having a bottom merging into an annular 55 bead adjacent the bottom and the bead in turn merging into an annular flange of less diameter than the bead, whereby a space is provided between said annular flange and the tubular portion of said ring, said space 60 permitting a tool to be inserted, and pressed against said flange for ejecting the compact plate from the ring.

3. The combination of a vanity case provided with a flange forming an annular 65 groove and a locking ring fitted into said groove with part of the ring projecting beyond the groove with a compact plate holding ring formed with a tubular portion 70 and a radial flange, said flange projecting beneath that part of said ring projecting beyond said groove, and said tubular portion being provided with a projection adapted to overlap part of the compact plate 75 to be held by said ring.

Signed at New York, in the county of New York and State of New York, this 5th day of March, 1928.

WILLIAM G. KENDALL.
